UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPOGRAPHICAL COMPOSING-MACHINE.

1,103,051.

Specification of Letters Patent.

Patented July 14, 1914.

Application filed April 8, 1912, Serial No. 639,130. Renewed May 27, 1914. Serial No. 841,367.

To all whom it may concern:

Be it known that I, DAVID SHERWOOD KENNEDY, a citizen of the United States, and a resident of Brooklyn, county of 5 Kings, and State of New York, have invented a new and useful Improvement in Typographical Composing - Machines, of which the following is a specification.

My invention relates to typographical 10 composing machines, such as linotype machines of the general organization represented in Letters Patent of the United States, No. 436,532, to O. Mergenthaler, wherein circulating matrices are released 15 from a magazine in the order in which their characters are to appear in print and then assembled in line, the composed line transferred to the face of a mold, the mold filled with molten metal to form a slug or linotype 20 against the matrices which produce the type characters thereon, and the matrices thereafter returned through a distributing mechanism to the magazine from which they started.

25 More particularly, the invention relates to the mold carrier or disk, which is ordinarily provided with two or more molds of different size, any one of which may be brought into operative position, as desired.

30 In ordinary practice, this disk is actuated by a pinion which receives its motion from a pin or stud on a collar fast on the driving shaft; and in order to change the mold, it is necessary to shift the pinion forward

35 by hand, thereby disengaging it from the driving pin or stud, and then to turn it relatively to the shaft in order to rotate the disk and bring another mold into operative relation to the other parts, after

40 which the pinion is again engaged with the pin. In order to avoid the inconvenience of this method of adjustment, I preferably employ a normally disengaged hand crank or equivalent device, arranged in such manner that its actuation serves both to draw the pinion forward and then to rotate it to adjust the disk, after which the crank or other member is automatically disengaged and remains at rest.

45 In the accompanying drawings I have shown my improvements as applied to a linotype machine, but obviously they are capable of broader application and may be employed in variant forms, which will suggest themselves to those skilled in the art,

and in connection with other styles of typographical machines, such for instance as those designed to produce type and the like instead of slugs or linotypes, as in the present instance.

Referring to the drawings: Figure 1 is a front view of a portion of a linotype machine, having my invention applied thereto, certain parts being removed to show the mold disk, etc.; Fig. 2 is a transverse vertical section thereof, taken substantially on the line 2-2 in Fig. 1, and showing also the pot and disk rotating means; Fig. 3 is a detached view showing one position of the adjusting means, on an 60 enlarged scale and partly broken away; Fig. 4 is a similar view of the said means in another position, partly in section; and Fig. 5 is a vertical sectional view, taken substantially on the line 5-5 in Fig. 4. 65

Referring to Fig. 1, the mold disk or carrier E is provided with a plurality of molds of different size, in the present instance two such molds being illustrated and designated respectively by the numerals 1 and 2. The 70 disk E is rotated in the customary manner by the pinion D meshing therewith. Referring to the other figures of the drawing, the mold shaft B is mounted as usual in the frame A and is rotated in any suitable manner, as by the gearing B¹. On the shaft B is rigidly mounted the collar C, formed with the extended hub C², and with a projecting pin C¹ which imparts motion to the driving pinion D. The pinion D is loosely mounted 75 on the hub C² of the collar C, and is formed with a plurality of holes or recesses D² (only one being shown in the drawings) to engage the actuating pin C¹. The pinion D is in turn formed with an extended hub D¹ surrounding the shaft B, and within which is mounted the spring F disposed between an interior flange D³ of the hub D¹ and a collar or abutment B² on the shaft B, in such manner that the force of the spring tends 80 to move the pinion D inwardly and engage one or another of its holes D² with the actuating pin C¹. 85

Freely mounted at the end of the shaft B is a hand crank G, formed with an inwardly 90 projecting sleeve G¹ which embraces both the end of the shaft and the outer portion of the hub D¹. In addition to its rotary motion about the shaft, the crank G is also capable of a slight axial motion with rela- 95

tion thereto, it being held outwardly in its inoperative position by the spring H mounted between the crank and the collar B² on the shaft. The hub D¹ of the pinion D is exteriorly provided with a projecting pin I, and the sleeve G¹ of the crank G is formed with a corresponding recess having an inclined edge G² to engage the pin I.

The operation of the parts will now be readily understood. If it be desired to adjust the mold disk E so as to bring another mold thereon into operative position, the crank G is moved inwardly against the force of the spring H, and until the recess in the hub G¹ thereof is in position to engage the pin I on the hub D¹ of the pinion D. This movement of the parts is illustrated by dotted and full lines in Fig. 3. The crank G is now operated, and the inclined edge G² acts upon the pin I in such manner as to move the pinion D laterally against the force of the spring F, and to break the engagement between its hole D² and the actuating pin C¹. This position of the parts is illustrated in Fig. 4. Notwithstanding this lateral movement of the pinion D, it still meshes with the mold disk E, and the further operation of the crank rotates both pinion and disk until another hole D² in the pinion registers with the actuating pin C¹, the relative movement of the disk simultaneously bringing another mold thereon into operative position. The crank G is now released to free the engagement of the inclined edge G² with the pin I, whereupon the spring F moves the pinion D inwardly to engage its new hole D² with the actuating pin C¹, and simultaneously the spring H moves the crank G outwardly to its inoperative position, where it hangs idly until again connected with the parts in the manner described. As previously stated, many variations and modifications of my invention will suggest themselves to those skilled in the art and still be comprised within its scope.

Having thus described my invention, its construction and mode of operation, what I claim and desire to secure by Letters Patent of the United States is as follows:

1. In a typographical machine, the combination of a movable mold carrier, driving means therefor comprising a driving shaft and an actuating pinion, and rotary devices mounted upon the shaft and normally disconnected from the pinion but adapted to be connected therewith at will, the said devices acting in their rotary movement first to break the actuating connection between the pinion and shaft, and thereafter to turn the pinion to adjust the mold carrier to a different position.

2. In a typographical machine, the combination of a movable mold carrier, driving means therefor, and rotary devices mounted concentrically to the driving means and nor-

mally disconnected therefrom but adapted to be connected thereto at will, the said devices acting in their rotary movement first to break the driving connection between the carrier and driving means, and thereafter to 70 adjust the latter to alter the position of the carrier.

3. In a typographical machine, the combination of a movable mold carrier, driving means therefor comprising a driving shaft 75 and an actuating pinion, and manual devices mounted upon the shaft and serving by their continued movement in one direction first to break the connection between the shaft and pinion, and thereafter to turn the latter to 80 adjust the mold carrier to a different position.

4. In a typographical machine, the combination of a movable mold carrier, driving means therefor comprising a driving shaft 85 and an actuating pinion, and rotary manual devices turning about the axis of the shaft and rotatable both relatively to and conjointly with the actuating pinion, and adapted by the relative rotation to break the actuating connection between the pinion and shaft, and by the conjoint rotation to operate 90 the pinion to adjust the mold carrier to a different position.

5. In a typographical machine, the combination of a movable mold carrier, driving means therefor comprising a driving shaft and an actuating pinion, and manual devices capable of both an axial and rotary movement relative to the shaft, and adapted by 95 their axial movement to engage the driving pinion, and by their rotary movement to break the connection between the shaft and pinion and turn the latter to adjust the mold carrier to a different position.

6. In a typographical machine, the combination of a movable mold carrier, driving means therefor comprising a driving shaft and an actuating pinion, the latter being provided with a projecting stud, and manual 110 devices for operating the pinion at will to adjust the mold carrier, the said devices being formed with an inclined or cam surface to engage said stud, so as to break, the connection between the shaft and pinion. 115

7. In a typographical machine, the combination of a movable mold carrier, driving means therefor comprising a driving shaft and an actuating pinion, the latter being provided with a projecting stud, and a rotary crank for operating the pinion at will 120 to adjust the mold carrier, the said crank being formed with a recess having an inclined wall to engage the stud; whereby the continued rotation of the crank will shift the 125 pinion axially on the shaft to break the actuating connection between the two, and thereafter operate the pinion to adjust the mold carrier to a different position.

8. In a typographical machine, the com- 130

bination of a movable mold carrier, driving means therefor comprising a driving shaft and an actuating pinion, manual devices for operating the pinion at will, an abutment, 5 and springs on opposite sides of said abutment and bearing against the actuating pinion and manual devices respectively, for the purpose described.

9. In a typographical machine, the combination of a movable mold carrier, driving means for moving the carrier in the ordinary operation of the machine and comprising a driving shaft and an actuating pinion, and manual devices mounted upon the shaft

and movable both relatively to and conjointly with the actuating pinion and adapted by the relative movement to break the actuating connection between the pinion and shaft, and by the conjoint movement to operate the pinion to adjust the mold carrier 15 to a different position.

In testimony whereof I hereunto set my hand this 27th day of March, 1912, in the presence of two attesting witnesses.

DAVID SHERWOOD KENNEDY.
